L. BORDWELL

BEATER

Filed April 18, 1924

Patented July 3, 1928.

1,676,128

UNITED STATES PATENT OFFICE.

LAVERN BORDWELL, OF NEW YORK, N. Y.

BEATER.

Application filed April 18, 1924. Serial No. 707,365.

This invention relates to improvements in beaters and is more particularly directed to beaters adapted for culinary use, pertaining to that type of beater shown in Patents Nos. 5 892,856 of July 7, 1908 and Patent No. 1,437,957 of December 5, 1922, the former of which was granted to E. W. Ladd and the latter to L. Bordwell.

My present invention relates to improvements over both of these beaters as well as beaters now known and in use.

One of the objects of my improved beater is to provide a frame for the beater mechanism which is very rigid, thereby giving a 15 longer life to the beater.

Another object of my invention is to provide a one-piece frame in which the drive gear for the beater mechanism is mounted in a novel manner.

20 Another and further object of my invention is to provide a novel manner of attaching the operating handle to the beater mechanism drive gear so that the operating handle penetrates the frame of the beater and 25 rotates within it.

Another and further object of my invention is to provide a novel construction of bottom to the frame so as to permit my improved mounting of the beater gear wheels 30 in the frame.

A still further object of my invention is to provide a novel construction of drive gear for the beater mechanism.

Another and further object of my invention is to provide a beater which is simple 35 of construction, highly efficient in operation and cheap of manufacture.

Other further objects, novel features of construction, and improved results of my 40 invention will appear in the following description and accompanying drawings:

In the drawings:

Figure 1 is a side elevation of my improved beater.

45 Figure 2 is a vertical sectional view through the frame and driving mechanism of the beater taken on the line 2-2 of Figure 1.

Figure 3 is a bottom view of the frame 50 showing the positioning of the beater gears and the cut out portion of the frame.

In carrying out my invention I provide a frame formed of an integral piece of material, the ends 5 and 6 of which are suitably fastened in a handle 7. Below the upper ends 5 and 6 of the frame the two vertical

legs 8 and 9 of the frame are in separated parallel relation. The lower ends of the vertical legs 8 and 9 terminate in outwardly and slightly downwardly extending portions 60 10 which in turn terminate in vertical walls 11. The frame is provided with a bottom 12 which joins the vertical walls 11. The bottom is provided with a cut out portion 13, the purpose of which will be hereinafter described.

A pair of beaters 14 and 15 are mounted upon a suitable shaft 16, the upper ends of the shaft being suitably fastened in the vertical walls 11 of the beater frame. The construction and mounting of this shaft is common to the two patents mentioned herein. The shaft 16 is usually continuous, comprising two vertical legs joined at their bottom by a horizontal leg.

75 The beaters 14 and 15 carry upon their upper ends the gears 17 and 18. In my improved construction one of these gears is supported in a horizontal plane above the other and the teeth of the gears extend inwardly towards each other and overlap. This construction clearly appears in Figs. 2 and 3 of the drawings. The gear 18 abuts the bottom 12 of the frame while the gear 17 is mounted in the cut out portion 13 of the frame bottom, the gear abutting the bottom of the vertical wall 11. The teeth 17^a of the gear 17 extend inwardly above the teeth 18^a of the gear 18.

85 The vertical leg 9 of the beater frame is provided with an inward off-set 19, the purpose of which will be hereinafter described. The beaters 14 and 15 are driven through a vertically mounted drive gear 20 which is rotatably supported upon a rivet 21 or the like which penetrates the inward off-set 19 of the vertical leg 9 of the frame. The head 22 of the rivet lies within the off-set portion 19 while the head 23 of the rivet fastens the vertical portion 24 of the handle 25 to the vertical drive gear 20. It will be further seen that the drive gear 20 is provided with an opening 26. The vertical portion 24 of the handle 25 has its end cut out as at 27 to provide extending portions 28 and 29. These extending end portions 28 and 29 are adapted to extend inwardly through the vertical drive gear opening 26 and be crimped against the opposite face of the gear 20 as appears at 30. The purpose of the inward 105 off-set 19 of the vertical leg 9 of the housing is now apparent. This off-set permits the

rotation of the gear 20 without the crimped handle ends 28 and 29 striking the leg 9 of the frame.

The vertical leg 8 of the frame is provided with a circular cut out portion 31 to permit the rotation of the handle 25 in this leg of the frame. This cut out portion is slightly greater in diameter than the length of the vertical portion 24 of the handle 25.

10 The gear 20 is provided with narrow elongated teeth 32, which, as clearly appears in Figure 2 of the drawing, extend downwardly through and mesh with the gears 17 and 18 of the beaters. To insure that the teeth 15 of the vertical drive gear 20 do not strike the bottom 12 of the frame, the bottom is crimped downwardly at 33 and 34 to permit free rotation of this gear.

The handle 25 is provided with a common 20 form of hand or finger hold 35.

Attention is directed to the fact that I have provided a beater in which the supporting frame for the beater mechanism has two vertical legs. The frame is formed of 25 an integral piece. Due to this construction great rigidity is given to the beater which adds greatly to the life and durability of the mechanism.

The simplicity of mounting the vertical 30 drive gear and attaching the drive gear handle makes for cheapness of manufacture. The manner of attaching the drive gear handle is such as to make the handle attachment firm and durable.

35 The construction of the drive gear 20 is very simple and cheap of manufacture. Due to the fact that the beater gears overlap one another it is possible to provide the simple elongated gear teeth 32 of the drive 40 gear. It is not necessary to give any pitch to these gear teeth and this gear adds to the cheapness and simplicity of manufacture.

A comparison of my improved beater with 45 those double type of beaters now on the market will disclose the fact that a minimum number of parts are used in producing my device. The advantage of a small number of parts is obvious.

50 The use of my particular frame makes it unnecessary to provide any additional bracing or strengthening means between the beaters and the holding handle 7, as is so often found in devices designed for the 55 same purpose as my own.

Having thus described my invention what I claim and desire to protect by Letters Patent is:

60 1. A beater comprising a frame consisting of separated parallel legs, an operating wheel pivotally connected with one of the parallel legs, a handle connected with the said wheel, the other parallel leg passing around the said handle and pivot, for the 65 purpose described.

2. A frame for a beater or the like, comprising a pair of vertical legs in spaced relation, a housing formed in the lower end of the frame, the lower wall of the housing having an opening therein, one vertical leg 70 having an off-set portion, and the other vertical leg having an opening, for the purpose described.

3. A frame for a beater or the like, comprising a pair of vertical legs in spaced relation, 75 a housing carried by the lower ends of the legs and formed integral therewith, the upper ends of the legs fastened together in a handle, a gear pivoted to one of said legs, a handle attached to the said gear, the other leg passing around the pivot and the said handle, for the purpose described.

4. A frame for a beater or the like, comprising a pair of vertical legs in spaced relation, one vertical leg having an off set portion, 85 a gear mounted on said off set portion between the vertical legs, the other vertical leg having an opening, an operating handle for the vertical gear extending through said opening and rotating therein, and the operating handle having extending ends extending through an opening in the gear and crimped upon the side of the gear adjacent the off set in the first mentioned vertical leg. 90

5. A beater of the type described, comprising a frame carrying a beater mechanism, a driving gear for the beater, beater gears supported from the frame, one of said gears in a horizontal plane above the other, the teeth of the beater gears overlapping one 100 another, and the teeth of the driving gear elongated and extending downwardly through the overlapped teeth of the beater gears, for the purpose described. 95

6. A beater of the type described, comprising a frame carrying a beater mechanism, a driving gear for the beater, beater gears supported from the frame, one of said gears being supported below the frame and the other within the frame bottom whereby one of said gears is in a horizontal plane 110 above the other, and a driving gear in operative engagement with the beater gears, for the purpose described.

7. A continuous piece frame for beaters or the like, comprising a pair of vertical legs in spaced relation, the upper ends of the legs fastened in a handle, a housing formed by the lower ends of the legs, one vertical leg having an off set portion between the vertical legs, a driving gear mounted upon the off set portion of the said vertical leg and rotatably supported between the legs, an operating handle for the driving gear, the vertical leg opposite the off set portion 120 being provided with an opening, and an operating handle for the driving gear extending through said opening and rotatable therein, for the purpose described. 125

8. A beater of the type described com- 130

prising a frame consisting of two upwardly extending leg portions, a driving gear journaled on one leg portion, the other leg portion having an enlarged opening located in line with the center of the said gear, and a handle having at its inner end a flat portion passing through the said opening and secured to the said gear, whereby the flat portion revolves in the said opening.

10 9. A beater of the type described comprising a frame having a beater mechanism, a driving gear for the beater, beater gears supported from the frame and extending in opposite directions, the gears overlapping and extending through and beyond the teeth of the said operating gear for the purpose described.

10. In a beater of the type described, a frame having a housing formed in the lower end thereof, the lower wall of said housing having a cut-out portion forming an opening, a driving gear, a pair of beater gears, one of said beater gears positioned below the lower wall of the housing and the other beater gear positioned in the opening of the lower housing wall, for the purpose described.

11. In a beater of the type described, a frame having a housing formed in the lower

end thereof, the lower wall of said housing having an opening therein, a driving gear, a pair of beater gears, one of said gears positioned below the lower wall of the housing and abutting the under side thereof, and the other beater gear positioned in the opening of the lower wall housing and abutting the lower end of the side wall of the housing, for the purpose described.

12. In a beater of the type described, the frame having a housing formed in the lower end thereof, the lower wall of said housing having a cut-out portion forming an opening, a driving gear, a pair of beater gears, one of said beater gears positioned below the wall of the housing and the other beater gear positioned in the opening of the lower housing wall, the teeth of the beater gears overlapping one another, the teeth of the driving gear elongated and extending downwardly through the overlapping teeth of the beater gears, and the lower wall of the housing provided with depressed portions at its ends to permit a clearance of the elongated driving gear teeth.

In testimony whereof I hereunto affix my signature.

LAVERN BORDWELL.
